UNITED STATES PATENT OFFICE.

ROBERT CARLISLE, OF CINCINNATI, OHIO, ASSIGNOR TO THE THOMAS GIBSON COMPANY, OF SAME PLACE.

DESIGN FOR A WATER-CLOSET BOWL AND BASE.

SPECIFICATION forming part of Design No. 16,841, dated August 10, 1886.

Application filed March 20, 1886. Serial No. 196,037. Term of patent 14 years.

To all whom it may concern:

Be it known that I, ROBERT CARLISLE, a citizen of the United States, residing at Cincinnati, in the county of Hamilton, State of Ohio, have invented a new and original Design for a Water-Closet, of which the following is a specification, reference being had therein to the accompanying drawings.

My invention comprises a design for a water-closet bowl and base, the bowl proper being of any desired shape, while the base of the same is entirely closed both at its sides and ends, as clearly shown in the annexed drawings, in which—

Figure 1 is a side elevation of the same. Fig. 2 is a front elevation thereof, and Fig. 3 is a horizontal section of the base or pedestal.

In the illustrations, A represents a water-closet bowl or basin, and B is the base or pedestal of the same, which base has a molding, C, at its lower edge.

D is a fillet at the junction of the bowl and base, the latter being made with flat vertical sides, as seen in Fig. 2, and with rounded ends, as represented in Fig. 3.

25

I claim as my invention—

1. The design for a water-closet bowl and base, as described and shown, which consists of the bowl A and closed base B, the latter having rounded ends and flat vertical sides, as 30 shown.

2. The design for a water-closet bowl and base, as described and shown, which design includes the bowl A and closed base B, the latter having rounded ends, flat vertical sides, 35 a base-molding, C, and fillet D.

In testimony whereof I affix my signature in presence of two witnesses.

ROBERT CARLISLE.

Witnesses:

JAMES H. LAYMAN,
SAML. S. CARPENTER.
